UNITED STATES PATENT OFFICE.

EDWARD J. MOUNTAIN, OF NEW YORK, N. Y.

ARCH AND ANKLE SUPPORT.

1,094,585.

Specification of Letters Patent. Patented Apr. 28, 1914.

Application filed March 7, 1912. Serial No. 682,107.

To all whom it may concern:

Be it known that I, EDWARD J. MOUNTAIN, a subject of the King of Great Britain, and a resident of the city of New York, borough of Manhattan, in the county and State of New York, have invented a new and Improved Arch and Ankle Support, of which the following is a full, clear, and exact description.

The invention relates to footwear, and its object is to provide a new and improved arch and ankle support in and for a shoe or boot, for preventing weakening or breaking down of the bony arch of the foot, and to restore broken down arches, by the use of a slightly resilient plate arranged permanently in the hollow arch of the boot or shoe, or in other words, below the plantar surface of the arch of the foot, and constructed in such a manner as to focus the weight as nearly as possible to the center of the foot and to equalize the weight of the body on the foot by distributing the said weight on the foot to all parts of the foot alike, thus supporting simultaneously both the longitudinal bony arch as well as the transverse bony arch of the foot, and balancing the latter to prevent lateral twisting; the plate, owing to its position, stiffness and curvature, also serving as an ankle support. Heretofore devices of this character have utilized or consisted in stiffening or supporting plates of varying widths, shapes and proportions, some of which have been arched longitudinally and sometimes slanted transversely, and have differed from my invention in that they have not conformed to the natural arch and position of the bones of the foot, both longitudinally and transversely. For instance, in places where the cross-section of the normal foot presents a concave line, the plate intended to support this portion is sometimes flat, and where a plate is provided having a curved cross-section, this curved cross-section extends only through a part of the plate, and other parts are left in such form that they do not properly support the portions overlying them. Moreover, in some instances resiliency is sought by supporting the plate upon springs or other elastic devices.

My invention consists of novel features and parts and combinations of the same, which will be more fully described herein-after and then pointed out in the claims.

A practical embodiment of the invention

is represented in the accompanying drawings forming a part of this specification, in which similar characters of reference indicate corresponding parts in all the views.

Figure 1 is a longitudinal sectional elevation of the improvement as embodied in a left shoe, in which appears the outline of the bony structure of the foot; Fig. 2 is an inverted plan view of the inner sole and plate, and showing the outline of the bony structure of the foot; Fig. 3 is a cross-section of the improvement on the line 1—2 of Fig. 1; Fig. 4 is a cross-section of the plate forming a part of my improvement on the line 3—4 of Fig. 6; Fig. 5 is a cross-section of the same plate on the line 5—6 of Fig. 6; Fig. 6 is a perspective view of the resilient plate.

The shoe illustrated in the accompanying drawings consists essentially of the upper A, the outer or main sole B, the insole C, and the heel D. Interposed between the outer sole B and the insole C, at the hollow arch of the boot or shoe, is arranged a plate E made of a stiff and yet resilient material such as steel or the like, and secured at its ends by rivets F or other fastening devices to the under side of the insole C. This plate, while resilient to such a degree as to yield somewhat and avoid the shock of walking, is yet sufficiently stiff to provide a firm support to the arch, and especially because of its peculiar curvature, to support that part of the arch on the inside of the foot under the ankle. To this end, the plate E is arched in a longitudinal direction, as shown in Fig. 1, and also arched in a transverse direction, as indicated in Fig. 3, and the insole C overlies the plate E, that is, conforms to the shape thereof, as will be readily understood by reference to Figs. 1 and 3. By reference to Fig. 1, it will be noticed that the curvature given to the plate E in a longitudinal direction corresponds approximately to the longitudinal arch of the bony structure of the foot, and the transverse arch of the plate E conforms to the transverse arch of the bony structure of the foot, as indicated in Fig. 3. It will also be noticed that the side edges of the plate E are curved inwardly and the curvature of the arch along the inner side edge E' of the plate E is more pronounced than the curvature along the outer side edge E² of the plate E. Now by this arrangement, the top of the inner side edge E' is higher than the

top of the outer side edge E^2 , and the rear end E^3 of the plate E is somewhat narrower than the front end E^4 , and the rear portion is preferably concaved for about one-third 5 of the length of the plate, while the front two-thirds is convexed, and the edge E^4 extends obliquely to conform to the beginning of the tread of the outer sole B. That is to say, the edge E^4 extends along a line 10 about one-half inch back of the edge or beginning of the tread of the sole of the natural foot, or what is sometimes called the ball of the foot. It is an oblique line; therefore, the arch of the plate along the line E' 15 has a greater spread, as it also has a greater spring, than the arch along the line E^2 . The edge E^4 is slightly bent up or reversed in order that it may not unduly wear or chafe the sole where it bears upon the latter. 20 In practice, the front end E^4 of the plate E rests on the outer sole B, approximately at the beginning of the tread of the outer sole, while the rear end E^3 of the plate E rests on the outer sole B at the heel portion thereof, as plainly indicated in the drawings. The 25 rear portion E^3 of the plate E is concaved to form a support to the forward end of the *os calcis* bone, so that the rear lower portion of this bone is permitted (tends) to swing forward and the arch of the bony structure 30 is thus raised.

By reference to Figs. 2 and 3, it will be noticed that the plate E is arranged with its longitudinal axis approximately in the middle 35 of the insole and below the tarsal, metatarsal and the rear ends of the phalangeal bones, with the exception of the fifth metatarsal bone, which latter lies outside the outer edge of the plate E, the extension of 40 insole acting as its support. As the curvature of the plate E closely follows the curvature of the arches formed by the tarsal, metatarsal and phalangeal bones of the foot and the surface of the plate is formed so 45 as to be approximately parallel to the arches, an exceedingly strong and natural support for the whole arch of the bony structure of the foot is had, and as the plate is somewhat resilient, it relieves the bones of undue jars 50 when the person is walking. The plate E, on account of being rigidly secured to the insole C, is at all times in the same relative position to the arches of the bony structure, and thus prevents lateral twisting of the foot 55 and thereby affords an ankle support. By the shape, proportions and arrangement described, the plate E scientifically corresponds to the anatomical shape and arrangement of the bones of the wearer's foot, in such a manner that the natural arch formed by the tarsal, metatarsal and the rear ends of the phalangeal bones is properly supported, to prevent weakening or breaking down 60 of this portion of the wearer's foot, and by the use of a shoe provided with the plate 65

described, a broken down arch can be readily restored to its original and natural shape. By the arrangement described, the weight of the body is focused near the center of the foot, and is then distributed through the 70 foot equally to all such parts of the foot as are supported by those parts of the shoe that touch the ground, owing to the curvature given to the plate E in both its longitudinal and transverse directions, and to the 75 location of the plate E, according to the arrangement of the bones in the foot of the wearer, which bones form a longitudinal as well as a transverse arch, in accordance with which the arches of the plate E are shaped. 80 By having the front end of the plate E terminating at or near the beginning of the tread of the sole, it is evident that when the wearer walks the plate does not interfere with the bend of the shoe, especially on the 85 forward step.

It will be observed from an inspection of the drawings, that the support is arched longitudinally and that the height of the arch is considerably greater on the inner 90 than on the outer side, that is, the support is shaped to conform to the normal arch of the foot. This construction supports the foot in its natural position, thus permitting the natural expansion and contraction of the 95 muscles, and the said muscles are strengthened by this natural use, thus overcoming the deformity of the foot, and restoring it to its normal condition.

It will, of course, be understood that, 100 while I have illustrated my improvement as designed for and applied to a left foot or shoe, it is intended to be utilized for both feet, the shape and arrangement being reversed to apply to the right foot.

I do not limit myself to the exact form or proportion shown in the drawings and described, nor to any particular material, as in all of these respects my invention is capable of variation without departing from 110 the spirit of my invention.

But what I do claim as new and desire to protect by Letters Patent, is:

1. In a boot or shoe, a stiff yet resilient supporting plate, the said plate being arched upwardly longitudinally to conform to the normal arch of the foot, the upper surface of the anterior portion of the plate being convex from side to side, and the upper surface of the posterior portion concave from 115 side to side.

2. In a boot or shoe, a stiff yet resilient supporting plate, the said plate being arched longitudinally to conform to the normal arch of the foot, the upper surface of the anterior portion of the plate being convex from side to side, and the upper surface of the posterior portion concave from side to side, the inner edge of the plate being concave and the outer approximately straight 120 125 130

and of lesser length than the inner edge, the longitudinal arch being greatest at the inner side of the plate.

3. A stiff yet resilient supporting plate for use with a boot or shoe, the said plate being arched upwardly longitudinally, the said arch being of greater height at its inner edge to cause the upper surface of the plate to face upwardly and outwardly to conform to the normal arch of the foot, the inner edge of the plate being concave and the outer approximating to the corresponding side of the shoe sole and of lesser length than the inner edge, the upper surface of the anterior portion of the plate being convex from side to side, and the upper surface of the posterior portion concave from side to side.

4. In a boot or shoe, a stiff yet resilient supporting plate arched upwardly longitudinally, the arch on the inside edge having shorter radii than the arch on the outer edge, and said plate having its anterior portion arched upwardly transversely, and its posterior portion arched downwardly transversely.

5. A stiff yet resilient supporting plate for use with a boot or shoe, having a longitudinal arch, the outer edge being arched on greater radii than the inner edge, and having reverse transverse curvatures, the upper surface of the anterior portion being convex and the upper surface of the posterior portion being concave.

6. A stiff yet resilient supporting plate for use with a boot or shoe, having a longitudinal arch, the outer edge being arched on greater radii than the inner edge, and having reverse transverse curvatures, the upper surface of the anterior portion being convex and the upper surface of the posterior portion being concave, the front edge of said plate extending substantially parallel to the line of joints of the normal foot, and being slightly bent in reverse of the arch along the forward point of support.

7. In a boot or shoe, a stiff yet resilient supporting plate arched upwardly longitudinally, the arch on the inside edge having shorter radii than the arch on the outer edge, and said plate having its anterior portion arched upwardly transversely.

8. A stiff yet resilient supporting plate for use with a boot or shoe, said plate being arched upwardly longitudinally for its whole length, the inner side edge of the plate having a higher arch relative to the horizontal plane than the arch on the outer side edge of the plate, and the upper surface of the anterior portion of the plate being convex from side to side, while the upper surface of the posterior portion is concave from side to side.
